Attorney.

UNITED STATES PATENT OFFICE.

URBANA D. ALEXANDER, OF CANNONSBURG, PENNSYLVANIA.

ELBOW FOR STOVEPIPES.

SPECIFICATION forming part of Letters Patent No. 627,633, dated June 27, 1899.

Application filed December 31, 1898. Serial No. 700,858. (No model.)

To all whom it may concern:

Be it known that I, URBANA D. ALEXANDER, a citizen of the United States, residing at Cannonsburg, in the county of Washington and State of Pennsylvania, have invented certain new and useful Improvements in Elbows for Stovepipes; and I do hereby declare the following to be a full, clear, and exact description of the invention, such as will enable others skilled in the art to which it appertains to make and use the same.

My invention relates to elbows, and particularly to elbows used for stovepipes; and the particular object of the invention is to construct the elbow in such shape or form as to admit of its being opened or unfolded for convenience in packing and shipping.

The invention combines simplicity, efficiency, and durability, and is, further, cheap to manufacture.

The invention consists in certain novel features and details of construction, as will be hereinafter described, and finally pointed out in the claim.

In the drawings, Figure 1 is a side elevation of an elbow embodying my invention, the device being shown in its closed or normal position ready for use. Fig. 2 is a similar view, the elbow being opened into the position for convenience in packing. Fig. 3 is a central vertical sectional view showing more clearly the manner in which the different parts or sections are secured together. Fig. 4 is a perspective view of the elbow shown in the open position, and Fig. 5 is a similar view of several elbows nested.

Similar letters of reference indicate corresponding parts in the different figures of the drawings.

I will now describe my invention, which is constructed as follows:

The elbow is formed of five distinct pieces *a*, *b*, *c*, *d*, and *e*, which are secured together in such a manner as to form two independent sections *A* and *B*. These sections *A* and *B* are hinged or pivoted together at one of their ends, as shown at *f*, the purpose of which is to admit said sections *A* and *B* to be opened without becoming entirely separated. The pivots also serve to hold said sections in a rigid position at this point when the device is in use.

The section *A* is formed of three parts *a*, *b*, and *c*, the part *b* being provided with flanges *h*, which overlap the parts *a* and *c*. Said parts are secured together by rivets or in any other suitable and convenient manner.

The section *B* is formed of two parts *d* and *e*, one or both of which are provided with flanges *i*, which, together with the rivets *j*, hold said parts in a rigid position relative to each other, or both sections may be stamped out in one piece each and formed into the proper shape by suitable machinery.

The section *B* of the elbow is provided with tongues *g* for engaging the outer end of the section *A* and holding it in its normal position when in use.

The operation of my invention is as follows: Assuming the device to be in its normal position and it is desired to prepare it for shipment, all that is necessary to do is to grasp the two sections *A* and *B* at the opposite ends from the hinge or rivets and pull them into the open position, as shown in Fig. 2. When in this position, they are in a position to be packed one within the other. It will be readily seen that a greater number of elbows made after my invention can be packed in a much smaller space than can be done with the class of elbows now in use. When the elbows have reached their destination, they are removed from the package and closed, after which they are ready for use.

Having described my invention, what I claim is—

A stovepipe-elbow consisting of two longitudinal sections pivotally connected together and adapted to be swung longitudinally in relation to each other whereby the sections may be brought into operative relation or moved from such relation for the purpose of nesting the elbows, substantially as shown and described.

In testimony that I claim the foregoing as my own invention I have hereunto set my hand, in the presence of two witnesses, at Cannonsburg, in the county of Washington and State of Pennsylvania, this 27th day of December, A. D. 1898.

URBANA D. ALEXANDER.

Witnesses:

FRED ALEXANDER,
MARK M. DECKER.
